LATCHING DEVICE

Berthold Knauer, East Norwalk, Conn., assignor
to Pitney-Bowes Postage Meter Co., Stamford,
Conn., a corporation of Delaware

Application August 10, 1943, Serial No. 498,047

9 Claims. (Cl. 248—25)

This invention relates to a device for securing a detachable meter unit to a machine base of a metered mailing machine.

In metered mailing machines, a meter unit is adapted to be mounted on a powered machine base and, through a manually controlled locking member, is adapted to be locked in an operative position or is adapted to be released to a non-operative position.

In the device herein described, an improved arrangement is provided for locking the meter unit to the base, wherein the manually controlled member is adapted to be placed in a locking position by applying manual pressure to a knob end thereof and is arranged in an unlocking position by effecting rotation of the knob. Each of said knob movements will control the movement of a latch to a locking or unlocking position respectively.

It is one object of the invention therefore, to provide an improved arrangement for locking a detachable unit to a machine base by a manually controlled member, whereby pressure on the manual member will effect locking, and rotation of the manual member will control unlocking of the detachable unit.

It is another object to provide an improved arrangement for locking a detachable unit to a base by first positioning the detachable unit on vertically disposed locating pins to prevent horizontal displacement and by latching the detachable unit against vertical displacement.

It is another object to provide a plunger controlled latching mechanism having spring means associated therewith, whereby upon effecting withdrawal of the plunger from a latch engaging position, initial rotation of the plunger will effect a spring charging action, which charged spring will permit a subsequent latching operation to be effected by merely depressing the plunger.

With the above and other objects in view, which will appear as the description proceeds, the invention resides in the combination and arrangement of parts and in the details of construction hereinafter described and claimed, it being understood that various changes in the precise embodiment of the invention herein disclosed may be made within the scope of what is claimed without departing from the spirit of the invention.

A preferred embodiment of the invention is illustrated in the accompanying drawings, wherein:

Fig. 1 is a plan view of a meter unit mounted

upon a base, with parts of the meter broken away and parts in section;

Fig. 2 is a vertical sectional view taken along the line 2—2 of Fig. 1 showing the latching mechanism in a latched position;

Fig. 3 is a sectional view similar to Fig. 2, but showing the latching mechanism in an unlatched position;

Fig. 4 is a vertical sectional view taken along the line 4—4 of Fig. 2; and

Fig. 5 is a fragmentary sectional view similar to a portion of Fig. 4, showing the various parts in a position agreeing with the unlatched arrangement of Fig. 3.

Referring to the drawings in detail, the meter unit is indicated generally at 10, which unit contains a printing head 11 and register mechanism indicated at 12, whereby printing may be effected in the printing of a predetermined value postage stamp upon mail matter, and the values thereof may be registered in a register 12. Said meter unit may be attached to or detached from a power driven machine base 13.

The meter unit 10 is adapted to be properly positioned upon the base by meter locating pins 14—14, which pins project vertically upward from the upper surface of the machine base 13. Sockets 15—15, which are located within the lower surface of the meter unit 10, are adapted to fit over the pins 14—14 when the meter unit is positioned on the machine base. When in said latter position, the meter unit is fixed against horizontal displacement.

Within the base, a hooked latch lever 16 is pivotally mounted at 17 upon a supporting bar 18, which bar is also pivotally mounted on a fixed bearing 20. By means of a spring 19, said latch lever 16 is adapted to be normally urged to a latch release position relative to a latch bar 21, fixed within the meter 10.

To control the position of the latch lever 16, a manually controlled member is provided as generally indicated at 22, which comprises a plunger 23, slidably positioned within a bearing 24 in a wall of the base 13, and a bearing 25 in a bracket 26 carried by said base 13. A sleeve 27 mounted on said plunger 23 has a semi-circular cam portion 28, terminating in shoulders 29 and 31. An end slot 32 is provided within the sleeve 27, which slot is engaged by a pin 33 projecting from the plunger 23. Said sleeve 27 is adapted to receive rotative movement when the plunger is rotated, and the plunger will be permitted to move axially as a result of the pin and slot connection.

A collar 34 is pinned to the plunger 23 and has a slot 35 in the periphery thereof. A coil spring 36, coiled around the plunger 23, has one end anchored in the collar 34 and the opposite end anchored to the bracket 26, and is normally adapted to provide endwise pressure between the collar 34 and a thrust washer 30 bearing against the inner face of the sleeve 27.

Cooperating with the cam shoulder 31, is a pin 37 projecting from bracket 26, and cooperating with slot 35 in collar 34, is a pin 38, projecting from the bracket 26.

In operation, let it be assumed that the meter unit 10 has been positioned upon the machine base, with the parts in the position as shown in Fig. 3, the latch lever 16 being in a released position. To place the latch lever 16 in a latching position, a knob 39 is depressed to effect engagement of the end of the plunger 23 with the latch lever 16 to thereby force said latch lever to a locking position relative to the latch bar 21, as indicated in Fig. 2. The collar 34, which is pinned to the plunger 23, will move with the plunger to a position beyond the end of the stop pin 38, and owing to a previous winding of said spring 36 during rotation of the knob 39, in a manner to be latter described, the face of the collar 34 will be moved by the spring into engagement with the pin 38 and thus retain the plunger in its latching position. Also, the sleeve 27 will have been rotated to cause cam 28 to rock the latch supporting lever 18 about its pivot and thereby draw the latch lever 16 downwardly tight against the upper surface of the latch bar 21. When in this position, the meter unit 10 is locked against both vertical and horizontal displacement, upon the machine base 13.

When releasing the latch lever 16 from a latching position, the knob 39 is initially rotated in a counterclockwise direction until the shoulder 31 of the cam 28 engages the stop pin 37, which engagement will control the position of the collar 34 such that the slot 35 is opposite the stop pin 38. Endwise pressure of the spring 36 will then cause the collar 34 to move sidewardly, thus effecting engagement of the pin 38 with the slot 35, as in Fig. 5. Also, during rotation of the knob 39, the spring 36 is wound tighter to provide the force which, as previously described, will be used in the next subsequent latching operating to effect rotation of the sleeve 27 and collar 34. The plunger 23 now having been withdrawn to the position of Fig. 3, the spring 19 will have rocked the latch lever 16 about its pivot 17 to a released position.

Having described the invention, what is claimed is:

1. In a device of the character described for effecting the locking of a detachable unit to a base, means whereby the detachable unit is fixed against horizontal displacement on the base when placed thereon, a latch member associated with the base and adapted to be manipulated from a position outside the base to lock said detachable unit against vertical movement on the base; latch control means comprising a manually controlled plunger having one end projecting beyond the base and the other end aligned with and adapted to engage the latch member to move same to a latching position relative to the detachable unit, said plunger having longitudinal and rotative movement, whereby, upon effecting manual pressure against the projecting end thereof, the plunger moves inward against the latch member to effect latching, and spring controlled means associated with said plunger, whereby upon initiating rotation of the plunger, it is adjusted to a position

where it is subsequently urged to a withdrawn position by the spring controlled means to effect latch movement to a non-latching position.

2. In a device of the character described, the combination with a detachable unit and a supporting base therefor, of means to normally prevent horizontal displacement of the detachable unit relative to the base, and manually controlled latch means associated with the base to prevent vertical displacement of the detachable unit comprising, a latch lever within the base movable to or from a latching position relative to the detachable unit, a settable plunger having one end aligned with said latch lever, said plunger having an inward axial motion to effect engagement with and movement of the latch lever to a latching position, and rotational motion to initiate control for effecting movement of the latch lever to a released position, and spring means associated with said plunger adapted to effect pressure to move the plunger to either a latching or a released position.

3. In a device of the character described for effecting the locking of a detachable unit to a base, means whereby the detachable unit is fixed against horizontal displacement on the base when placed thereon, a latch member supported within the base and adapted to engage a portion of the detachable unit and lock same against vertical displacement on the base, latch control means comprising a manually controlled plunger rod having one end aligned and engageable with the latch member to move same to a latching position with relation to the detachable unit when manual pressure is applied to the opposite end thereof, a spring coiled around the plunger rod and having one end fixed relative to the rod and the other end fixed relative to the base, and means whereby said spring is adapted to cooperate with the plunger to retain said plunger in either a latching or a non-latching position.

4. In a latch mechanism, a latch lever, a plunger rod having one end aligned with said latch lever and movable endwise in one direction to effect movement of the latch lever to a latching position and in an opposite direction to permit movement of the latch lever to a non-latching position, spring controlled means associated with said plunger to effect control in retaining the plunger in either of the two named positions, said spring controlled means including a spring coiled around said plunger and having one fixed end, a collar fixed to said plunger and having the other end of the spring anchored thereto, and a stop pin associated with the base adapted to engage an opening in said collar when the plunger is withdrawn from engagement with the latch lever, and adapted to engage one face of the collar to obstruct withdrawal of the plunger after the plunger has been moved to a latch engaging position.

5. In combination with a base and detachable unit a latch lever mounted in the base, a plunger rod aligned with said latch lever and manually movable to engage and control movement of the latch lever to a latching or a non-latching position relative to the detachable unit, plunger control means including a spring coiled around said plunger and having one end fixed relative to the base, a collar having an opening therein and fixed to said plunger and having the other end of the spring anchored thereto, a stop pin fixed relative to said base and adapted to engage the opening in said collar when the plunger is withdrawn to a non-latching position relative to the latch lever.

means to manually grip and rotate the plunger and thereby align the collar opening with the stop pin when withdrawal of the plunger is to be effected, said rotation being adapted to effect the winding of the spring, whereby, when the collar is moved free of the stop pin as the plunger is moved to a latching position relative to the latch lever, the collar will be rotated by the prewound spring to an obstructing position relative to the stop pin and thereby retain the plunger in a 10 latch lever engaging and latching position.

6. In combination with a base and detachable unit, a latch member supported in the base and adapted to be moved to a latching position relative to the detachable unit, latch control means including a plunger having longitudinal movement when effecting latching, and rotational movement when initiating latch release, a collar fixed to said plunger having a slot therein, a stop pin fixed relative to the base and adapted to either engage said slot or one face of the collar, and a spring coiled around said plunger and having one fixed end and the other end anchored to said collar, whereby, after the plunger has been moved to a latch engaging position and is rotated to effect latch release the slot in the collar will become aligned with the stop pin and move to a locking position relative to the pin under pressure of the spring, thereby retaining the spring in a charged condition, such that when the plunger is moved inward to a point where the collar is free of the pin, the collar will be rotated by the charged spring to effect contact between the pin and the face of the collar and thereby retain the plunger in an advanced or latching position.

7. In combination with a base and detachable unit, a latch member supported in the base and adapted to be moved to a latching position relative to the detachable unit, a pivotal support for said latch member, latch control means including a plunger having longitudinal movement wherein one end thereof is adapted to engage the latch member when effecting latching, and having rotational movement when initiating latch release, a collar on said plunger having a slot therein, a stop pin fixed relative to said base adapted to either engage said slot or one face of the collar, a spring coiled around said plunger and having one fixed end and the other end anchored in said collar, whereby, when the plunger is in a latch engaging position the plunger and collar may be rotated until the slot becomes aligned with the stop pin, whereupon the collar will move to a locking position relative to the pin under pressure of the spring, thereby retaining the spring in a charged condition, such that when the plunger is moved inward to a point where the collar is free of the pin, the collar will be rotated by the charged spring to effect contact between the pin and one face of the collar and thereby retain the plunger in an advanced or latching position, and a cam carried by the plunger movable to

engage the latch member support when the plunger is rotated by said spring, thereby effecting the rocking of the support about its pivot to provide clamping engagement of the latch member with the detachable member.

5 8. In a device for latching a movable member to a stationary member, a pivotal latch lever having a hooked end which is adapted to be moved into latching engagement with a portion of the movable member, means to urge the latch lever to a non-latching position, a plunger rod supported by the stationary member and having one end aligned with the latch lever, whereby, when the plunger is depressed the latch lever will be urged thereby to a latching position, a collar having a slot therein and fixed to said plunger rod, a sleeve arranged to rotate with said rod but permit longitudinal movement of the rod therethrough, a spring coiled around said rod between the collar and sleeve and having one end fixed relative to the stationary member and one end fixed relative to the rod, and a stop pin associated with said collar and adapted to bear against one face thereof when the rod is depressed to a latch engaging position and to engage the slot when the rod is retracted from a latch engaging position, said slot being normally rocked out of alignment with said pin by torsional tension effect of the spring on the collar when the rod is depressed and being moved into alignment when the plunger rod is manually rotated for the release of the latch lever.

9. In a device for latching a movable member to a stationary member, a pivotal latch lever having a hooked end which is adapted to be moved into latching engagement with a portion of the movable member, means to urge the latch lever to a non-latching position, a plunger rod supported by the stationary member and having one end aligned with the latch lever, whereby, when the plunger is depressed the latch lever will be urged thereby to a latching position, a collar having a slot therein and fixed to said plunger rod, a sleeve arranged to rotate with said rod but permit longitudinal movement of the rod therethrough, a spring coiled around said rod between the collar and sleeve and having one end fixed relative to the stationary member and one end fixed relative to the rod, a stop pin associated with said collar and adapted to bear against one face thereof when the rod is depressed to a latch engaging position and to engage the slot when the rod is retracted from a latch engaging position, said slot being normally rocked out of alignment with said pin by torsional tension effect of the spring on the collar when the rod is depressed and being moved into alignment when the plunger rod is manually rotated for the release of the latch lever, and stop members associated with the sleeve to limit the rotary motion of the plunger rod.

BERTHOLD KNAUER.
